UNITED STATES PATENT OFFICE.

HORACE ERVIE, OF OGONTZ, PENNSYLVANIA.

AUTOMOBILE DOOR-CURTAIN.

1,120,608.

Specification of Letters Patent. Patented Dec. 8, 1914.

Application filed February 2, 1911. Serial No. 603,180.

To all whom it may concern:

Be it known that I, HORACE ERVIE, a citizen of the United States, residing in Ogontz, county of Montgomery, State of Pennsylvania, have invented certain Improvements in Automobile Door-Curtains, of which the following is a specification.

My invention relates to certain improvements in the side curtains of an automobile of the "touring car" type, or type having a movable top so that the full height of the doorway is opened when the door is swung on its pivot for the ingress or egress of persons using the car.

One object of my invention is to so construct the curtain at the doors that it forms practically part of the door and will swing with the door so as to open the full height of the doorway, allowing for the easy ingress or egress of persons using the car.

A further object of the invention is to make the extension device detachable from the door so that it can be packed away in a small compass.

In the accompanying drawings:—

Figure 1, is a side view of sufficient of an automobile to illustrate my invention; the curtain extension of the door being mounted in position; Fig. 2, is a view, similar to Fig. 1, with the curtain removed; Fig. 3, is a sectional view on the line 3—3, Fig. 1, showing the curtains in position; Fig. 4, is a view, similar to Fig. 3, with the curtains detached; Fig. 5, is an enlarged sectional view on the line 5—5, Fig. 1, showing the door closed; Fig. 6, is a view, similar to Fig. 5, showing the door partly opened; Fig. 7, is a perspective view showing the door partly opened; Fig. 8, is an inside perspective view of the door; Fig. 9, is a perspective view of the section which is secured to the body of the automobile and which overlaps the front edge of the door; Fig. 10, is a perspective view of the door with the attachment mounted in place without the curtains; Fig. 11, is an enlarged sectional view of the door similar to Fig. 3; Fig. 12, is a detached view of the attachments; and Fig. 13, is a view of a modification.

I have illustrated my invention as applied to an automobile having a collapsible top, known as a "touring car top" in which the top can be turned back and folded at the rear seat. In this type of top, the side curtains are detachable and are usually rolled

into a small compass and packed in a compartment of the automobile. My invention, however, can be used with any type of car either on the rear or front doors where detachable curtains are employed to protect the sides during stormy weather and where a folding door is not used.

It will be understood that while I have illustrated my invention as applied to automobiles, it can be applied to any vehicle in which it is desired to form an inclosing extension of the door.

Referring to the drawings, A is the body of an automobile.

B is the door of the ordinary type hinged at b and, in the present instance, opening outward.

C is the top supported by braces of any of the usual types.

C' is the detachable back curtain.

C" is the detachable forward curtain.

B' is the curtain which extends above the door and C" is a curtain strip, which is mounted between the edge of the door curtain B' and the forward curtain C".

In order to support the curtain B' so that it will swing out with the door, I provide a detachable frame, which is carried by the door. Secured to each end of the door B are sockets e—e, made as clearly shown in Fig. 11, and these sockets can be set in the woodwork of the door or secured to the inner side of the door, as desired. The method of securing the sockets will depend considerably upon the type of door to which the sockets are applied.

D—D are two uprights having extensions d adapted to the sockets e. These extensions are preferably tapered, as illustrated in Fig. 11, and are quadrangular in cross section, so that they will not turn. On the uprights D are shoulders d' which rest upon the upper edge of the sockets e when the parts are neatly fitted together and while I have shown the extensions of the uprights quadrangular in cross section and tapered, it will be understood that they may be of any shape desired and if they are round a set screw may be used to secure them in a fixed position in the sockets. I find that by making the extensions fit the sockets it is not necessary to use other fastenings. Each upright has a tapered upper end d² projecting beyond a shoulder d³ and mounted on the uprights is a cross bar F having sockets f—f, tapered to receive the tapered

ends d^2 . These ends may be of any shape desired, but I find that by making them tapered a tight fit is assured. The uprights D—D are of metal, while the cross bar F 5 is preferably made of wood so as to avoid rattling, which is a common occurrence in vehicles where two loose metal parts are connected.

Near the upper edge of the door, preferably located on the outside thereof, are turn buttons b' and on the outer surface of the cross bar are turn buttons f' . The curtain B' has button-holes arranged at intervals through which the buttons b' and f' extend. 10 Thus the curtain is stretched between the upper edge of the door B and the cross bar F. The forward edge of the curtain B' is turned around the front upright D and the edge of the curtain is fastened to the body 15 thereof by a series of spring fastenings or buttons b^2 , Fig. 8.

I preferably extend the curtain B' to the rear of the door and attach it to the buttons a on the main frame and also to buttons c' at the lower edge of the top, as shown by dotted lines in Fig. 1, so that when the door is open the curtain will simply bend on a line with the door as in Fig. 6, and there will be no opening at this point. 20 Thus it will be seen that when the door is open the section of the curtain above the door opens with the door and consequently the full height of the doorway between the floor of the car and the top is exposed so 25 that a person can readily enter or leave the car. When it is desired to dispense with the curtains, the door curtains B' can be readily unfastened and the uprights D—D and cross bar F can be readily detached and 30 stowed away in a small compass with the curtains.

In some instances, instead of making the cross bar detachable from the uprights, as in Fig. 11, the cross bar may be hinged to 45 the uprights, as in Fig. 13, but the objection to this construction is that the parts cannot be packed in so small a compass as where they are made separate, as in Fig. 12.

In order to make a neat fit between the outer edge of the door curtain and the fixed curtains of the top, I provide a section C³, Fig. 9, which has a casing c^2 for the reception of an upright D', shaped at the bottom the same as the upright D and adapted 55 to a socket a' in the body A, Fig. 10. The

opposite edge of the section C³ is perforated for the reception of buttons which are secured by the curtains C² or one of the bows which support the top and the rear edge of this curtain is so proportioned that it overlaps the front edge when the door is closed. 60

In order to close the space between the upper edge of the door curtain and the top C, I make the lapel of the top so that it 65 will extend over the edge of the door curtain when the door is closed, and all that is necessary is to run the finger along the front edge of the door curtain and along the top edge when the two projecting edges 70 will be forced out and will lie along the outer edge of the door curtain, preventing rain entering the body of the automobile.

While I have shown, in Fig. 3, the top C greater in width than the body A of the 75 automobile, in some types of automobiles, or other vehicles, the top may be on a vertical line with the body, and in this construction the uprights will be straight instead of bowed. The amount of bow will depend 80 entirely upon the width and type of top used and the design of the body of the automobile.

In some instances, the door curtain B' may be permanently attached to the cross 85 bar F and the cross bar used as a pole upon which to roll the curtain when it is stored away, but I prefer to use a construction where the curtain is entirely detachable from the other parts. 90

I claim:

The combination of a detachable curtain for vehicles having a hinged door and a movable top; a door having sockets at its upper edge near each end; an upright detachably and rigidly mounted in each socket; a continuous cross bar detachably mounted on the ends of the uprights and extending from one upright to the other; a curtain detachably secured to the door 100 and to the cross bar, the curtain, when in position, holding the cross bar and the uprights rigidly to the door. 95

Intestimony whereof, I have signed my name to this specification, in the presence 105 of two subscribing witnesses.

HORACE ERVIEN.
